COMBINATION PHONOGRAPH TABLE AND RECORD ALBUM RACK

Samuel E. Adler, Chicago, Ill., assignor to Admiral Corporation, Chicago, Ill., a corporation of Delaware

Application November 16, 1953, Serial No. 27,623
Term of patent 14 years

(Cl. D33—14)

To all whom it may concern:

Be it known that I, Samuel E. Adler, a citizen of the United States, residing at Chicago, in the county of Cook, State of Illinois, have invented a new, original, and ornamental Design for a Combination Phonograph Table and Record Album Rack, of which the following is a specification, reference being had to the accompanying drawings, forming a part hereof.

Fig. 1 is a perspective view of a combination phonograph table and record album rack, showing my new design;

Fig. 2 is an end elevational view thereof, the lower portion being broken away; and

Fig. 3 is a top plan view of the same, a corner portion of the top being broken away.

I claim:

The ornamental design for a combination phonograph table and record album rack, as shown and described.

SAMUEL E. ADLER.
